(57) **CLAIM**

The ornamental design for a morcellator, as shown and described.

DESCRIPTION

FIG. 1 is a right side view of a morcellator in accordance with the new design;

FIG. 2 is a left side view thereof;

FIG. 3 is a bottom perspective view thereof;

FIG. 4 is a front perspective view thereof; and,

FIG. 5 is a rear perspective view thereof.

The broken line showing is for illustrative purposes only and forms no part of the claimed design.

1 Claim, 4 Drawing Sheets

FIG. 4

FIG. 5
